MEANS FOR MAKING BRASSIÈRES

William Rosenthal, New York, N. Y., assignor to
 Maiden Form Brassiere Co., Inc., New York,
 N. Y., a corporation of New York

Application January 10, 1933, Serial No. 650,966

2 Claims. (Cl. 223—19)

This invention relates to a brassière made of knitted fabric in which the pockets for the bust are free of seams. It also relates to an improved method of making such a brassière by means of which the pockets may be shaped as desired, irrespective of their original shape as knit, and to a method of shaping the pockets to give them the desired form and characteristics not found in the original knitted fabric.

10 The fabric from which the brassière of this invention may be made can be knitted on a circular knitting machine of the type which produces what is known as "gussets". That is to say, pockets which are knit into the fabric during the knitting operation without any seams, such as would be required in order to form pockets in flat knitted fabric.

Fabric knit in this manner has never been practical for brassières for the reason that the pockets cannot be given the proper shape and the elasticity and other characteristics of the fabric in its original knitted form allows the pockets to stretch and to lose whatever shape they have. By my invention I overcome these defects and secure a brassière with seamless pockets of the size and shape desired, irrespective of their original knitted shape, and which will retain their shape thereafter.

30 The nature of my invention will be clearly understood from the following specification and drawings, of which—

Figure 1 is a diagrammatic illustration of a piece of fabric knit on a circular knitting machine showing the pockets in their original irregular conical shape;

Fig. 2 is a view of a stretching frame over which the fabric is stretched during the process whereby it is given its final shape and characteristics;

Fig. 3 illustrates diagrammatically two pockets cut from the original knitted material and stretched upon the form of Fig. 2;

Fig. 4 illustrates the shape and outline of the pockets after removal from the frame;

Fig. 5 illustrates diagrammatically the manner in which the stretched fabric is cut to separate the portions which are used to form the respective pockets of the brassière; and

Fig. 6 shows the completed brassière and the manner in which these pocket pieces are combined with the rest of the brassière structure.

As already stated, the knitted material from which my brassière may be made can be knit on a circular knitting machine which produces gussets or pockets in the fabric. These pockets, shown at 1 and 2 in Fig. 1, consist of excess ma-

terial formed during the knitting and are without seams. It is of course highly desirable that there should be no seams in brassière pockets, but heretofore their production has been impractical because of the impossibility of securing the correct pocket shape in circular knit fabric and of producing flat knit fabric having seamless pockets.

The fabric, produced as described above, with the integral seamless pockets of irregular conical form, is first dyed and then cut as shown in Fig. 1 to separate the part including two similar pockets. Then the cut edges are sewn to prevent raveling and the fabric is stretched over the frame 3, shown in Fig. 3, which may be made of any suitable material and which has the outline desired for the pockets of the finished brassière found in its upper edge 4. A rod 5 provided on either side with outwardly projecting needles or points 6 is adjustably attached to the frame by means such as forks 7 and is provided with means for maintaining it in any adjusted position, such as screws 8 engaging with slots 9 in the frame.

The fabric, including two unformed pockets as above described, is stretched over this frame, as shown in Fig. 3, and the edges caught upon needles 6. Rod 5 is then pulled down until the fabric is firmly stretched over the frame with the pockets taking the outline of the upper edge 4 thereof. Then rod 5 is secured with the fabric in this stretched condition by tightening screws 8. This not only gives the desired outline to the pockets but also flattens them.

The fabric, thus stretched, is steamed and then allowed to cool and dry upon the frame. When it is removed it will be found that the pockets have lost their original shape and outline and have now taken permanently the outline of edge 4 of the frame and also, instead of being generally conical in shape, are exceedingly flat, as shown in Fig. 4. It will be found that the pockets will retain this outline and flatness throughout the life of the brassière and will not revert to the original shape.

After the fabric has thus been steamed and set, the individual flat pockets are cut therefrom, as shown in Fig. 5, after which they are sewn together and connected to the rest of the brassière to form the completed article, as shown in Fig. 6.

In this way I convert a fabric which is utterly useless for brassières into a very useful type of fabric for that purpose and obtain a brassière having seamless flat pockets of any desired outline, irrespective of their shape and outline in the fabric as originally knit. Since the original size and shape of the pockets have no effect, within wide limits, upon the size and shape of the fin-

ished pockets I am able to produce a large variety of pocket sizes and shapes from identical fabric, thus greatly simplifying and reducing the cost of manufacture.

5 The pockets thus shown and shaped may be incorporated in any desired brassière construction, that shown in Fig. 6 consisting of the two pockets 10 and 11 attached to each other as shown at 12, the opposite ends being attached to additional 10 fabric 13 and 14 to extend around the back, one of which terminates in a piece of elastic 15 provided with hooks or eyes which connect with corresponding hooks or eyes on the other piece of fabric, as at 16. The usual shoulder straps 17 15 may also be provided, as shown. The proportions of the brassière will, of course, be determined by the dimensions of its different elements, whereas the shape, size and outline of the pockets themselves are determined by the outline and dimensions of the stretching frame as described above. 20 It will be understood, of course, that the process described may be modified so that, for example, pockets are shaped individually instead of in pairs and in numerous other ways without exceeding the scope of this invention. 25

Having now described the object and nature of

my invention, what I claim as new and useful and desire to secure by Letters Patent is:

1. A frame for stretching and shaping brassière pockets comprising a base rod, a pair of bars secured adjacent the ends of said base rod at right angles thereto, an upper framework edge mounted on and carried by said bars, said edge including a portion at each end extending from said bars so as to be converging away from the base rod and a portion extending from each of said converging portions and converging in the opposite direction to a point of union, and adjustable means carried by said bars for vertically tensioning the fabric of a material stretched upon said frame. 10

2. A frame for stretching and shaping brassière 15 pockets comprising a base rod, an upper framework edge secured to said base rod comprising a pair of V-shaped portions one leg of each portion being attached to said base rod and the other leg of each portion united to the corresponding leg 20 of the other whereby the framework edge has a pair of raised, separated points, pointing in the same direction and adjustable means carried by said framework for tensioning the fabric of a material stretched upon said frame. 25

WILLIAM ROSENTHAL.
